CLAIM

The ornamental design for a flea comb, as shown and described.

DESCRIPTION

FIG. 1 is a front top perspective view of a flea comb with the teeth in the closed position in accordance with the new design;

FIG. 2 is a front bottom perspective view thereof;

FIG. 3 is a rear bottom perspective view thereof;

FIG. 4 is a top elevation view thereof;

FIG. 5 is a bottom elevation view thereof;

FIG. 6 is a left side elevation view thereof;

FIG. 7 is a right side elevation view thereof;

FIG. 8 is a front elevation view thereof;

FIG. 9 is a rear elevation view thereof;

FIG. 10 is a front top perspective view of a flea comb with the teeth in the extended position in accordance with the new design;

FIG. 11 is a front bottom perspective view thereof;

FIG. 12 is a rear bottom perspective view thereof;

FIG. 13 is a top elevation view thereof;

FIG. 14 is a bottom elevation view thereof;

FIG. 15 is a left side elevation view thereof;

FIG. 16 is a right side elevation view thereof;

FIG. 17 is a front elevation view thereof; and,

FIG. 18 is a rear elevation view thereof.
